UNITED STATES PATENT OFFICE.

EDWIN G. HATCH, OF NEW YORK, N. Y.

APPARATUS FOR GENERATING MOTIVE FLUID.

1,049,580.

Specification of Letters Patent.

Patented Jan. 7, 1913.

Application filed January 16, 1912. Serial No. 671,454.

To all whom it may concern:

Be it known that I, EDWIN G. HATCH, a citizen of the United States, and a resident of the borough of Brooklyn, county of Kings, city and State of New York, have invented certain new and useful Improvements in Apparatus for Generating Motive Fluid, of which the following is a specification, accompanied by drawings.

10 This invention relates to apparatus for generating gaseous or vaporous motive fluid for prime movers, particularly of the piston or turbine type, which depend for their operation upon the pressure, or on the velocity, 15 or in part on both the pressure and velocity of the motive fluid supplied.

The objects of the invention are to obtain increased efficiency and economy of operation in both the motive fluid generating apparatus and in the prime mover, by utilizing as much as possible of the heat ordinarily lost in the disposition of the products of combustion, and in the water jackets.

In accordance with this invention, either 25 simple or explosive combustion of charges of a gaseous or vaporous fuel mixture is caused to take place in a suitable closed and jacketed combustion chamber having supply and exhaust ports, but without movable interior working parts, such as a piston, so 30 that practically all the heat of combustion or explosion is available for heating the chamber walls and generating steam in the water passages. By jacket is meant all the 35 passages forming a part of the combustion chamber, through which the water and steam circulate. The products of combustion are then mixed with the steam so generated, preferably after the products have 40 left the combustion chamber and if desired, a diluent, as air, may be added to the mixture. This motive fluid comprising products of combustion, steam and preferably a diluent are supplied to the prime mover at 45 temperatures and pressures best suited for the operation of the particular type of prime mover used.

In apparatus of the improved character described, in which the combustion chamber 50 is not itself a mechanical motor, but a true generator, means should preferably be provided independent of the operation of the

combustion chamber and prime mover, for supplying fuel mixture to the combustion chamber to start the apparatus, and I have 55 devised further improvements in my apparatus, for increasing the saving of heat, as will hereinafter appear.

To all of these ends the invention consists of the apparatus shown in its preferred embodiment in the accompanying drawings, in which—

Figure 1 is a diagrammatic top plan view partly in horizontal section, illustrating the apparatus for carrying out the invention; 65 Fig. 2 is an enlarged detail transverse sectional view of the combustion chamber on the line 2—2 of Fig. 1, looking in the direction of the arrows. Fig. 3 is an enlarged detail transverse sectional view of the fuel 70 mixer on the line 3—3 of Fig. 1, looking in the direction of the arrows; Fig. 4 is an enlarged detail longitudinal sectional view of the motive fluid mixer on the line 4—4 of Fig. 1, looking in the direction of the arrows; Fig. 5 is a detail longitudinal sectional view on the line 5—5 of Fig. 1, looking in the direction of the arrows, and illustrating a portion of the valve operating device; Fig. 6 is a diagrammatic plan view 80 partly in horizontal section of a modification of the apparatus; Fig. 7 is an enlarged detail longitudinal sectional view on the line 7—7 of Fig. 1, looking in the direction of the arrows, showing a form of valve mechanism, and Fig. 8 is an enlarged detail view of the contact device on line 6—6 of Fig. 6. 85

Referring to the drawings, A represents the working cylinder of a suitable prime mover, as a piston engine, to which motive fluid is to be supplied through the pipe B leading to the valve chest C of the engine. The combustion chamber is represented at D in Fig. 1 and shown in transverse section in Fig. 2, illustrating a suitable form of water jacket which will hereinafter be described more particularly. The combustion chamber proper is a compartment or space E without movable interior working parts and communicating through the exhaust aperture F and pipe G with a motive fluid mixer H shown in detail in Fig. 4. The water jacket of the combustion chamber D also communicates by means of the pipe J with 100

the mixer H, in which the products of combustion from the combustion chamber and the steam from the water jacket are mixed and supplied through the pipe B to the working cylinder A. A diluent, as for instance, air, may also be admitted to the mixer H through the pipe K.

- A fuel storage reservoir L is preferably connected by means of the pipe O to the 10 supply port of the combustion chamber D and fuel mixture is supplied to the storage reservoir L under pressure, as by means of the compressor P of any suitable type, driven by a suitable motor or engine, as the 15 engine cylinder Q. A fuel mixer R shown in detail in Fig. 3 communicates with the compressor P and means are provided for supplying a gaseous or vaporous fuel and a supporter of combustion to said fuel mixer 20 R. Oil may be supplied to the mixer R from an oil reservoir S which may be so elevated that oil will always flow into the mixer R, and air may be supplied to the fuel mixer R from the air reservoir T, or 25 atmospheric air may be drawn from the outlet U. Water for the jackets of the engine A, combustion chamber D, and fuel storage reservoir L, may be supplied from a suitable water storage tank or pump V. Inlet 30 and outlet valves W and X are provided in the pipes O and G respectively for the combustion chamber D by means of which the supply and exhaust to and from the combustion chamber are controlled and I 35 prefer to provide automatic controlling mechanism for said valves, illustrated at Y, capable of suitable adjustment and connected to be operated by any suitable moving part of the apparatus, as from the piston 40 rod Z.

While any suitable form of water jacket may be provided for the combustion chamber D, I prefer the form shown in Fig. 2, in which the combustion chamber is provided with a dome a to which water is supplied through the pipe b. Within the outer shell of the combustion chamber is shown in this instance a casing c having tortuous longitudinal connecting passages there- 45 through communicating at one end with the inlet apertures d and communicating at the other end with the outlet aperture e. An annular space f is provided between the casing c and the shell of the combustion chamber, so that the jacket water may flow freely 50 through all the passages provided and be subjected throughout its course to the heat of combustion generated in the combustion chamber proper E within the casing c. The 55 casing c as shown in Fig. 2, is also connected to the combustion chamber walls as by means of the hollow neck g, communicating with the combustion chamber proper E as by means of the perforations h, by

means of which an initial charge or charges 65 of fuel mixture may be supplied to the combustion chamber to start the apparatus in generation. Any suitable arrangement of tortuous passages for the jacket water and steam may be provided, not necessarily the 70 construction shown.

Any suitable water jackets may be provided for the engine cylinder A and the storage reservoir L and as shown, the water supply V is connected by pipe j to the engine jacket and thence by pipe k to the fuel storage reservoir jacket which communicates by means of pipe b with the dome a of the combustion chamber. The outlet e of the combustion chamber jacket is connected by pipe J with the motive fluid mixer H. It is not necessary to use a jacketed fuel storage reservoir, but in case this construction is provided, the jacket water may be first heated at the engine 85 cylinder A and further heated in the jacket of the fuel storage reservoir. The heated water or possibly steam or perhaps a mixture of water and steam passes through the pipe b to the combustion chamber water 90 jacket and steam emerges from the outlet e of the combustion chamber water jacket, through pipe J to the motive fluid mixer H where the products of combustion, steam and preferably air, are brought together and 95 the final working fluid produced. Any suitable means may be provided for causing the water to circulate through the jacket system. A controlling valve o is preferably provided on the pipe j connecting with the 100 water tank or pump V and a controlling valve p is provided on the steam pipe J. A controlling valve q is provided on the motive fluid supply pipe B connecting with the engine A, and pressure gages r and s are 105 preferably provided on the pipes J and B respectively. The motive fluid mixer H is preferably so constructed that the velocity of the entering steam through the pipe J will aid in exhausting the products of combustion from the combustion chamber, and to this end I provide concentric nozzles t and u in the mixer H converging to a contracted throat v. The interior steam nozzle t communicates with the steam pipe J, while 110 the outer nozzle u communicates with the pipe G leading to the exhaust from the combustion chamber, so that a device on the injector principle is in effect provided. An air passage w surrounds the nozzle u 115 and communicates with the air pipe K having the outlet to atmosphere at x controlled by the valve y. The air pipe K also connects by means of the pipe z with the air reservoir T, so that air under pressure may 120 be supplied to the motive fluid mixer H by manipulating the controlling valve 2 in the pipe z. Obviously the products of com-

bustion and steam may be exhausted to atmosphere through the outlet *x* if desired under certain circumstances.

The pump or compressor *P* is shown in this instance of the double-acting piston type, although any suitable type may be used, and comprises the cylinder *3* having the piston *4* connected by the piston rod *Z* to the piston *5* of the engine cylinder *Q*. Suitable spring controlled inlet and outlet valves *6* and *7* are provided for the cylinder *3* and as shown, the inlet valve chambers of the valves *6* communicate by pipe *8* with the fuel mixer *R*, a controlling valve *9* being provided at the inlet side of the compressor. The outlet valve chambers of the valves *7* are connected by the pipe *10* with the fuel storage reservoir *L* and check valves *11* are preferably provided in the branches of the pipe *10*, as shown. A pressure gage *12* may also be provided in pipe *10*. The fuel mixer *R* may be of any suitable type, but in this instance is preferably provided with the inner mixing chamber *13* and the outer jacket *14*. The mixing chamber proper *13*, is supplied with oil or other fuel from the oil reservoir *S* through the pipe *15*, and with air or other supporter of combustion from the air reservoir *T* through the pipe *z* and the pipe *16*. Both the oil and air pipes *15* and *16* preferably pass for at least a portion of their length through the exhaust pipe *17* connecting with the exhaust of the working cylinder *A*, and also connecting through the branch pipe *18* with the exhaust of the cylinder *Q*, so that the oil and gas pipes *15* and *16* are heated by the exhaust products of the apparatus. Pipe *17* communicates with the jacket *14* of the fuel mixer *R* and from thence the exhaust products are exhausted through the pipe *19* to the atmosphere or possibly to a condenser. Exhaust pipe *17* from the engine *A* is provided with a controlling valve *20* and exhaust pipe *18* from the engine cylinder *Q* is provided with the controlling valve *21*. If desired, the exhaust from the cylinder *Q* may pass to atmosphere through the pipe *22* controlled by the valve *23*, and the exhaust from engine *A* may pass to the atmosphere through the pipe *24* controlled by the valve *25*. By closing the controlling valve *26* in the pipe *16* leading to the air reservoir *T*, air may be drawn from the atmosphere through the inlet *U* controlled by the valve *27*. The oil reservoir *S* is also preferably jacketed and heated by the exhaust products, which are led to and through the oil reservoir jacket by the branch pipe *28*. Suitable means are provided for heating the fuel mixer *R*, in this instance, burners *29* being shown beneath the mixer connected by a pipe *30* to a carburetor *31* which in turn is connected by pipe *32* to the oil reservoir *S* and

controlled by the valve *33*. An adjustable opening *34* may be provided in the bottom of the mixer *R* through which the burners may be ignited.

Any suitable means may be provided for operating the engine *Q* to actuate the compressor *P*, but in this instance I prefer to operate the engine *Q* by means of a portion of the motive fluid generated. As shown, a pipe *35* connects the motive fluid mixer *H* with the valve chest *36* of engine *Q* and a branch pipe *37* connects the exhaust pipe *17* with the pipe *35*. Controlling valves *38* and *39* are provided for the pipes *35* and *37*, so that the exhaust products may pass directly to pipe *17* by closing valve *38* and opening valve *39*.

I have illustrated suitable means for automatically actuating the supply and exhaust valves *W* and *X* for the combustion chamber, and this apparatus designated at *Y* is capable of such adjustment, that the generation of motive fluid may be controlled in accordance with the load on the working cylinder. A main shaft *40* is revolvably supported in bearings *41* and provided with a crank wheel *42* at one end, the crank pin *43* of which is connected by the pitman *44* to the sleeve *45* fixed to the piston rod *Z*. Counter-shafts *46* and *47* are suitably mounted at each side of the main shaft *40*, as by means of the brackets *48* and *49* loosely supported on the main shaft *40*. The main shaft *40* is provided with the sprockets *50* and *51* connected by chains *52* and *53* to the sprockets *54* and *55* on said counter-shafts. The counter-shafts are provided with sliding sleeves *56* and *57* keyed to rotate therewith and having gears *58*, *59*, *60* and *61* mounted thereon. Cross arms *62* and *63* are connected to the sleeves *56* and *57* and slidable on the brackets *48* and *49*. These cross arms are provided with handles *64* by means of which they may be grasped and moved longitudinally on the brackets and at the same time the brackets may be rocked upon the main shaft *40*. Cam shafts *65* and *66* are mounted adjacent the counter shafts *46* and *47* and provided with pinions *67* and *68* adapted to mesh with either one of the adjacent gears, so that the shafts *65* and *66* may be driven at different speeds according to the adjustment of the apparatus. The shafts *65* and *66* are provided with the cams *69* and *70* adapted to operate the trips *71* and *72* on the valve stems *73* and *74* respectively of the valves *W* and *X*.

The trips *71* and *72* are connected to re-tracting springs *75* and *76* as shown in detail in Fig. 5. Assuming that valve *W* is open with the trip *71* in the position indicated in Fig. 5, it is obvious that the cam *69* rotating clockwise will permit the valve

to close under the influence of the spring 75, as the cam passes from contact with the trip 71. The time of closing may be regulated by the shape of the cam 69 and by the strength of the spring 75. The cam 69 and spring 75 may be so designed as to produce a quick closure of the admission valve W, so that the explosion, if explosive combustion is utilized, may occur in the combustion chamber immediately after the admission of the charge to the combustion chamber, while cam 70 should be designed to maintain the exhaust valve X open a relatively longer time and close more slowly in order to provide ample time for the products of combustion to pass out from the combustion chamber and mix with steam in the motive fluid mixer. It is to be understood that valve X is opened as the cam 70 actuates the trip 72 and cam 70 also rotates clockwise with the construction shown. A suitable igniter 75 may be connected by wires 76 and 77 to and through a battery 78 and to contacts 79 and 80, one of which is carried by the shaft 40. The cam 81 on the shaft 40 completes the circuit, in this instance, at every revolution of the main shaft 40.

The valve (not shown) in the valve chest 36 of engine cylinder Q may be actuated from any suitable moving part of the apparatus, in this instance, the valve stem 82 being connected to a sliding block 83 moving in the guideway 84. A pitman 85 is also connected to the sliding block 83 and to an eccentric 86 on the main shaft 40, so that the valve of engine cylinder Q is controlled by the revolutions of the valve 40.

In order to start the generation of the apparatus, means are provided operating independently of the operation of the combustion chamber and the prime mover. As shown, a nozzle 87 is connected to the pipe 8 leading from the fuel mixer R and controlled by valve 88. A flexible connection or other suitable connection 89 connects the nozzle 87 with a nozzle 90, Figs. 1 and 2, communicating with the hollow neck g in the walls of the combustion chamber D. A perforated adjustable hood 91 affords an additional supply of air around the nozzle 90 and a valve 92 of any suitable character controls the passage in the neck g. By closing the valve 9, leading to the compressor and opening the valve 88 leading to the flexible connection 89 and assuming that the other valves and connections in the apparatus are suitably adjusted, it is obvious that an initial charge or charges of fuel mixture will be supplied from the fuel mixer to the combustion chamber D, where the charge may be ignited thereby starting the generation of motive fluid. In starting the apparatus, it is assumed that fuel is supplied

to the burners 29 which are lighted to heat the mixer and the heat generated by the burners thoroughly vaporizes and heats the oil supplied from the oil reservoir S and the air supplied from the air reservoir T or inlet U. On starting, when the steam pressure gage indicates that steam is being generated at a sufficiently rapid rate, the motive fluid is admitted to the engine cylinder Q by suitably manipulating the valves and the compressor is started. The supply and exhaust valves W and X for the combustion chamber may be kept closed until pressure in the storage reservoir L has been built up, and after the generation of motive fluid is fully started, the flexible connection 89 is disconnected, the valve 92 for the passage g is closed, and the burners 29 turned off.

The fuel storage reservoir L may be omitted without affecting the principles involved, but the use of the reservoir is advantageous and it should have a greater cubical capacity than the combustion chamber. By using the reservoir L a compressed charge is introduced inside the combustion chamber quicker than would otherwise be the case and at a more uniform pressure and the number of strokes of the piston 4 in the compressor P per unit of time need not be the same as the number of explosions in the combustion chamber in the same time, but the compressor may be operated at any suitable speed to provide a proper supply pressure in the reservoir irrespective of the number of explosions in the combustion chamber.

On starting, the products of combustion first generated may pass to atmosphere through valve y and outlet z, or by closing valve 38 in the pipe 35 and opening valve 39 in the pipe 37, said products of combustion may pass directly to the exhaust pipe 17 and be utilized for heating the ingredients of the fuel mixture as they pass to the mixer R. A combustible gas may be used, if desired, instead of oil, without departing from the spirit of the invention, and different methods of vaporizing the oil fuel may be devised. The starting of the apparatus may be effected where a supply of compressed air is available by utilizing compressed air to start the operation of the engine cylinder Q, thus effecting compression through the operation of the compressor P and such operation may be carried on until a suitable pressure has been built up in the reservoir L.

In the modification of the apparatus shown in Fig. 6, an electric motor 100 is provided for operating the compressor P. The shaft 101 of the motor is provided with a pinion 102 meshing with the gears 103 and 104. Gear 103 is provided with a crank pin 105 connected by the pitman 106 to the

piston rod Z' of the compressor P. In this instance gaseous or vaporous fuel is preferably supplied to the compressor as by means of the pipe 107, while air is supplied to the pipe 108. Separate gas and air pipes 109 and 110 lead from the compressor to gas and air reservoirs 111 and 112. Check valves 113 and 114 are preferably provided in the pipes 109 and 110. The reservoirs 111 and 112 are preferably jacketed and supplied with jacket water through the pipe 115 having the controlling valve 116. Pipe 117 communicates with the water jacket of the combustion chamber D. The gas and air reservoirs 15 communicating with the combustion chamber proper by means of the pipes 118 and 119 are provided with the check valves 120 and 121 and the valve chests 122 and 123 containing suitable slide valves (not shown) 20 control the supply pipes 118 and 119. The exhaust pipe G leading from the combustion chamber is provided with the valve X, as in Fig. 1, having the valve stem 124 and trip 125. The steam pipe J communicates with 25 the mixer H, as in Fig. 1, and the mixer supplies the motive fluid to a motive fluid reservoir H', arranged in the engine supply pipe B. Suitable valve mechanism is provided for operating the valve X and the 30 supply valves in the chests 122 and 123, preferably actuated by the motor 100. On the shaft 126 is arranged a sliding sleeve 127 keyed thereto, provided with a sprocket 128 connected by chain 129 to sprocket 130 35 on shaft 131. Shaft 131 is provided with the pinion 132 adapted to mesh with pinions 133, 134 and 135. A bracket 136 connects the sleeve 127 to the shaft 131 and a handle 137 affords means for rocking the 40 bracket 136 about the sleeve 137. The gear shaft 138 is provided with a sprocket 139 connected by chain 140 with a sprocket 141 on a short shaft 142 carrying a cam 143 coöperating with the trip 125 on the 45 valve stem 124 of valve X. The igniter 175 for the combustion chamber is arranged substantially as in Fig. 1. The valve stems 145 and 146 are connected to suitable means for adjusting the throw of the valves and 50 thereby varying the admission of fuel mixture to the combustion chamber. Any suitable valve mechanism may be used for this purpose and I have illustrated diagrammatically in Fig. 7 the well-known Stephen- 55 son link motion by means of which the throw of the valve may be varied by adjusting the hand operating lever 147. This link motion will not be further described, as it is old and well-known.

60 Obviously a turbine supplied with working fluid may be substituted for the engine cylinder Q or the electric motor 100 for operating the compressor P or other suitable compressing means.

Obviously the invention is not limited to 65 the precise apparatus shown and described nor to the details of construction, for various devices may be devised for carrying out the objects of the invention, without altering the principles involved.

I claim and desire to obtain by Letters Patent the following:

1. In apparatus for generating motive fluid for prime movers, the combination of a closed jacketed combustion chamber having supply and exhaust ports, means for supplying water to said jacket, means for supplying charges of gaseous or vaporous combustible fuel mixture intermittently to said chamber under pressure, an igniter, and 75 means at the outlet end of the combustion chamber outside of the jacket for mixing the products of combustion with the steam generated in the jacket by the heat of combustion.

2. In apparatus for generating motive fluid for prime movers, the combination of a closed jacketed combustion chamber having supply and exhaust ports, means for supplying water to said jacket, means for 90 supplying charges of gaseous or vaporous combustible fuel mixture intermittently to said chamber under pressure, an igniter, and means at the outlet end of the combustion chamber outside of the jacket for mixing 95 the products of combustion with the steam generated in the jacket by the heat of combustion, and with a diluent.

3. In apparatus for generating motive fluid, the combination with a prime mover, 100 of a jacketed combustion chamber, means for supplying water to said jacket, means for supplying charges of gaseous or vaporous combustible fuel mixture intermittently to said chamber under pressure, an igniter, 105 means at the outlet end of the combustion chamber outside of the jacket for mixing the products of combustion with the steam generated in the jacket by the heat of combustion, and means independent of the 110 operation of the combustion chamber and the prime mover for supplying combustible fuel mixture to the combustion chamber to start the apparatus.

4. In apparatus for generating motive 115 fluid, the combination with a prime mover, of a jacketed combustion chamber, means for supplying water to said jacket, means for supplying charges of gaseous or vaporous combustible fuel mixture intermittently 120 to said chamber under pressure, an igniter, means at the outlet end of the combustion chamber outside of the jacket for mixing the products of combustion with the steam generated in the jacket by the heat of combustion, and with a diluent, and means independent of the operation of the combustion chamber and the prime mover for sup- 125

plying combustible fuel mixture to the combustion chamber to start the apparatus.

5. In apparatus for generating motive fluid, the combination with a prime mover, 5 of a combustion chamber provided with means for generating steam by the heat of combustion, means at the outlet end of the combustion chamber independent of the steam generating means for mixing the 10 steam with the products of combustion from the combustion chamber, and means independent of the operation of the prime mover and combustion chamber for supplying combustible fuel mixture to the combustion 15 chamber to start the apparatus.

6. In apparatus for generating motive fluid, the combination of a jacketed combustion chamber having supply and exhaust ports, means for supplying water to said 20 jacket, fuel storage means communicating with said chamber, means for supplying gaseous or vaporous combustible fuel mixture to said storage means under pressure, automatic means for controlling the admission 25 of the fuel mixture to the combustion chamber, a mixer connected to the exhaust of the combustion chamber, automatic means for controlling said exhaust connections, steam connections between the jacket 30 and mixer, and means for controlling said steam connections.

7. In apparatus for generating motive fluid, the combination of a jacketed combustion chamber, means for supplying water to 35 said jacket, storage means communicating with said chamber, means for supplying gaseous or vaporous combustible fuel mixture to said storage means under pressure, automatic means for controlling the admission of 40 the fuel mixture to the combustion chamber, a mixer connected to the exhaust of the combustion chamber, automatic means for controlling said exhaust connections, steam connections between the jacket and mixer, 45 means for controlling said steam connections, and means for supplying a diluent to said mixer.

8. In apparatus for generating motive fluid for prime movers, the combination of 50 a closed jacketed combustion chamber having supply and exhaust ports, means for supplying water to said jacket, means for supplying charges of gaseous or vaporous combustible fuel mixture intermittently to 55 said chamber under pressure, an igniter, means at the outlet end of the combustion chamber outside of the jacket for mixing the products of combustion with the steam generated in the jacket by the heat of combustion, and means independent of the operation 60 of the combustion chamber and the prime mover for supplying combustible fuel mixture to the combustion chamber to start the apparatus.

9. In apparatus for generating motive 65 fluid for prime movers, the combination of a closed jacketed combustion chamber having supply and exhaust ports, means for supplying water to said jacket, means for supplying charges of gaseous or vaporous 70 combustible fuel mixture intermittently to said chamber under pressure, an igniter, means at the outlet end of the combustion chamber outside of the jacket for mixing the products of combustion with the steam generated in the jacket by the heat of combustion, and with a diluent, and means independent of the operation of the combustion chamber and the prime mover for supplying combustible fuel mixture to the combustion 75 chamber to start the apparatus.

10. In apparatus for generating motive fluid for prime movers, the combination of a prime mover, a jacketed combustion chamber, means for supplying water to said 80 jacket, a compressor for supplying charges of gaseous or vaporous combustible fuel mixture intermittently to the combustion chamber, an igniter, means at the outlet end of the combustion chamber outside of the jacket for mixing the products of combustion with the steam generated in the jacket by the heat of combustion, and means independent of the prime mover for operating the compressor by the motive fluid gener- 85 ated.

11. In apparatus for generating motive fluid for prime movers, the combination of a prime mover, a jacketed combustion chamber, means for supplying water to said 100 jacket, a compressor for supplying charges of gaseous or vaporous combustible fuel mixture intermittently to the combustion chamber, an igniter, means at the outlet end of the combustion chamber outside of the 105 jacket for mixing the products of combustion with the steam generated in the jacket by the heat of combustion, means independent of the prime mover for operating the compressor by the motive fluid generated 110 and means for heating the fuel mixture by heat derived from the motive fluid generated at.

12. In apparatus for generating motive fluid for prime movers, the combination with 115 a prime mover, of a jacketed combustion chamber having supply and exhaust ports, means for supplying water to said jacket, fuel storage means communicating with the combustion chamber, a compressor for supplying gaseous or vaporous combustible fuel mixture to said storage means, an igniter, automatic means for controlling the supply 120 of fuel mixture to the combustion chamber, a mixer connected to the exhaust of the combustion chamber, and automatic means for controlling said exhaust connections, steam connections between the jacket and mixer 125

and means for controlling said steam connections.

13. In apparatus for generating motive fluid for prime movers, the combination with 5 a prime mover, of a jacketed combustion chamber having supply and exhaust ports, means for supplying water to said jacket, fuel storage means communicating with the combustion chamber, a compressor for supplying gaseous or vaporous combustible fuel mixture to said storage means, an igniter, 10 automatic means for controlling the supply of fuel mixture to the combustion chamber, a mixer connected to the exhaust of the combustion chamber, automatic means for controlling 15 said exhaust connections, steam connections between the jacket and mixer and means for controlling said steam connections, and means for operating the compressor by the 20 motive fluid generated.

14. In apparatus for generating motive fluid for prime movers, the combination with a prime mover, of a jacketed combustion chamber having supply and exhaust ports, 25 means for supplying water to said jacket, fuel storage means communicating with the combustion chamber, a compressor for supplying gaseous or vaporous combustible fuel mixture to said storage means, an igniter, 30 automatic means for controlling the supply of fuel mixture to the combustion chamber, a mixer connected to the exhaust of the combustion chamber, automatic means for controlling 35 said exhaust connections, steam connections between the jacket and mixer and means for controlling said steam connections, means for operating the compressor by the motive fluid generated, and means for heating the fuel mixture by heat derived 40 from the motive fluid generated.

15. In apparatus for generating motive fluid for prime movers, the combination with a prime mover, of a jacketed combustion chamber having supply and exhaust 45 ports, means for supplying water to said jacket, fuel storage means communicating with the combustion chamber, a compressor for supplying gaseous or vaporous combustible fuel mixture to said storage means, an igniter, 50 automatic means for controlling the supply of fuel mixture to the combustion chamber, a mixer connected to the exhaust of the combustion chamber, automatic means for controlling 55 said exhaust connections, steam connections between the jacket and mixer and means for controlling said steam connections, means for operating the compressor by the motive fluid generated, means for heating the fuel mixture by heat derived 60 from the motive fluid generated, and means independent of the operation of the combustion chamber and the prime mover for supplying combustible fuel mixture to the combustion chamber to start the apparatus.

16. In apparatus for generating motive 65 fluid for prime movers, the combination with a prime mover, of a jacketed combustion chamber having supply and exhaust ports, means for supplying water to said jacket, fuel storage means communicating with the 70 combustion chamber, a compressor for supplying gaseous or vaporous combustible fuel mixture to said storage means, an igniter, automatic means for controlling the supply of fuel mixture to the combustion chamber, 75 a mixer connected to the exhaust of the combustion chamber, automatic means for controlling said exhaust connections, steam connections between the jacket and mixer and means for controlling said steam connections, and means independent of the operation of the 80 combustion chamber and the prime mover for supplying combustible fuel mixture to the combustion chamber to start the apparatus.

17. In apparatus for generating high pressure motive fluid for prime movers, the combination of a closed jacketed combustion chamber having supply and exhaust ports, means for supplying water to said jacket, 90 means for intermittently producing combustion of charges of a gaseous or vaporous fuel mixture in said chamber, thereby heating the chamber walls and generating steam without doing other useful work in the combustion chamber, and means at the outlet 95 end of the combustion chamber outside of the jacket for mixing the products of combustion with the steam generated in the jacket and with a diluent.

18. In apparatus for generating motive fluid, the combination of a jacketed combustion chamber, means for supplying water to said jacket, means for intermittently producing combustion of charges of a gaseous 105 or vaporous fuel mixture in said chamber, a mixer connected to said chamber at its outlet end, and an injector nozzle in said mixer connected to said jacket.

19. In apparatus for generating motive 110 fluid, the combination of a jacketed combustion chamber, means for supplying water to said jacket, means for intermittently producing combustion of charges of a gaseous or vaporous fuel mixture in said chamber, a 115 mixer connected to said chamber at its outlet end, and concentric nozzles in said mixer connected respectively to the combustion chamber and to the jacket.

20. In apparatus for generating motive 120 fluid, the combination of a closed jacketed combustion chamber having supply and exhaust ports, means for supplying water to said jacket, separate reservoirs for gaseous or vaporous fuel, and a supporter of combustion, 125 connections between said reservoirs and the combustion chamber, means for intermittently producing combustion of charges

of gaseous or vaporous fuel mixture in the combustion chamber, and means at the outlet end of the combustion chamber outside of the jacket for mixing the products of combustion with the steam generated in the jacket.

21. In apparatus for generating motive fluid for prime movers, the combination of a prime mover, a jacketed combustion chamber having supply and exhaust ports, means for supplying water to said jacket, means for intermittently producing combustion of charges of a gaseous or vaporous fuel mix-

ture in said chamber, means for mixing the products of combustion with the steam generated, and means for heating the fuel mixture by heat derived from the motive fluid generated.

In testimony whereof I have signed this specification in the presence of two subscribing witnesses.

EDWIN G. HATCH.
